United States Patent Office.

FRANK W. MARSTON, OF BOSTON, MASSACHUSETTS.

Letters Patent No. 97,788, dated December 14, 1869; antedated November 30, 1869.

IMPROVEMENT IN FASTENINGS FOR CORSETS.

The Schedule referred to in these Letters Patent and making part of the same.

To all whom it may concern:

Whereas Letters Patent, dated December 15, 1868, and antedated December 2, 1868, were issued to P. H. Niles and F. W. Marston, both of the city of Boston, county of Suffolk, and State of Massachusetts, for Improvement in Corset-Fastenings; be it known that I, FRANK W. MARSTON, of the city of Boston, county of Suffolk, and State of Massachusetts, have invented a new and useful improvement in said corset-fastenings; and I do hereby declare the following to be a full and exact description of my invention, reference being had to the accompanying drawings, which form a part of this specification.

The object of my invention is to make the corset-fastenings described in the above-mentioned patent perfectly secure without depending upon the pressure of the body to keep them in place, and, at the same time, not to interfere with the detaching of the fastenings, as there described. This is fully effected by means of a spring, constructed, attached, and operated in the manner hereinafter set forth.

In the drawing—

Figure 1 is an elevation of two steels connected.

Figure 2 is an end section of the steels and fastenings, enlarged, showing the button *c* in the angle of the two slots *b* and *e*, and held securely in position by the convex head of the button engaging with the concavity *d*, and by the pressure of the spring upon it.

The spring *a*, shown at *B*, and broken off at *A*, is made of any suitable material, and is of the same size and shape as the clasp which it covers.

That end of the spring *a* farthest from the steel to which it is attached is formed with a concavity on its under side, of sufficient size to freely admit the convex head of the button.

This spring is riveted, with the clasp, to the steel, as shown in fig. 2, and thus practically becomes a part of the clasp.

I prefer this mode of constructing and applying a spring, for the purpose stated.

I make no variation in the operation of fastening or releasing the clasps, as described in the before-mentioned patent; but, in so fastening them, the head of the button *c* slips under the spring *a*, and enters into the concavity *d*, where it is held securely. The movement of the button, either upward through the vertical slot *b*, or back through the lateral slot *e*, is now impossible without the application of force in one or the other of those directions.

In releasing the fastenings by "relative endwise movement," the head of the button is forced out of the concavity, and then the whole button easily moves up and out of the vertical slot.

If the head of the button protruded through the clasp uncovered, it would, as in ordinary corset-fastenings, wear the clothing. The spring *a* makes a provision against this.

I do not wish to embody this idea in my claim; nor do I broadly claim the use of a spring for securing corset-fastenings; but

What I do claim, is—

The spring *a*, covering the clasp, when formed with a concavity, *d*, to engage with the head of the stud *c*, and retain it in position, substantially as described, and for the purpose set forth.

FRANK W. MARSTON.
